UNITED STATES PATENT OFFICE

132,586

DESIGN FOR A COMBINED CABINET PANEL AND CATCH OPERATOR

Earl Borchers, Rockford, Ill., assignor to American Cabinet Hardware Corporation, Rockford, Ill., a corporation of Illinois

Application August 16, 1940, Serial No. 94,463

Term of patent 7 years

To all whom it may concern:

Be it known that I, Earl Borchers, a citizen of the United States, residing at Rockford, in the county of Winnebago and State of Illinois, have invented a new, original, and ornamental Design for a Combined Cabinet Panel and Catch Operator, of which the following is a specification, reference being had to the accompanying drawing, forming a part thereof.

Figure 1 is a perspective view of a combined cabinet panel and catch operator showing my new design.

Fig. 2 is a sectional view taken on the line 2—2 of Fig. 1.

Fig. 3 is a fragmentary rear elevational view of the combined cabinet panel and catch operator shown in Fig. 1.

I claim:

The ornamental design for a combined cabinet panel and catch operator, substantially as shown.

EARL BORCHERS.
